UNITED STATES PATENT OFFICE.

MAURICE P. WHITNEY, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,396,695.

Specification of Letters Patent. Patented Nov. 8, 1921.

Application filed August 25, 1920. Serial No. 406,038.

To all whom it may concern:

Be it known that I, MAURICE P. WHITNEY, a citizen of the United States, residing at Elmira, in the county of Chemung and State of New York, have invented certain new and useful Improvements in Engine-Starters, of which the following is a specification.

My invention relates to a starter for engines such as internal combustion engines and has more particularly relation to the drive or transmission operatively connecting the prime mover such as an electric motor with a part of the engine to be started such as the flywheel thereof. The object of my invention is to provide a simple, efficient construction of such a drive and of the type in which reduction gearing is employed.

In the drawing Figure 1 is a sectional elevation of a starter apparatus embodying my invention and Fig. 2 an end view thereof with a portion broken away.

Referring to the embodiment of my invention which I have selected and herein shown for the purpose of making a clear and definite description of my invention the same comprises a prime mover such as an electric motor indicated at 1, an engine member or flywheel 2, and the drive or transmission which connects therebetween and which constitutes my invention. The motor frame has an end plate or cover 3 secured thereto in suitable manner as by means of screws 4 and having a portion depending below the lower line of the motor. A case 5 which substantially incloses the drive is secured in suitable manner as by the screws 6 to the plate 3.

The driving shaft 7 which is here the extended armature shaft of the motor is provided with an inner bearing 8 in the plate 3 and an outer bearing 9 in the casing 5. Upon this shaft there is mounted a pinion 10 capable of rotary movement therewith and longitudinal movement thereof. According to the construction being described this pinion has a smooth bore adapted to slide upon the smooth portion 11 of the shaft and is also provided with a hub 50 or sleeve extension 12 preferably integral with the pinion body and operatively connected with the shaft 7 in suitable manner as by means of the splines 13. This pinion has a comparatively wide face and is pro-

vided with spiral gear teeth for a purpose 55 hereinafter explained.

A parallel shaft or countershaft 14 is mounted within the casing 5, one end being journaled in the bearing 15 in the plate 3 and the other end in the bearing 16 in the 60 casing 5. To this shaft there is secured a gear 17 which has spiral gear teeth and with which the pinion 10 is always in mesh in every shifted position of such pinion owing to the wide face thereof. Upon this shaft 65 14 there is mounted a driving member which is here in the form of a pinion 18, having teeth adapted to engage the teeth 2^a of the flywheel 2 but which are normally out of engagement therewith as shown in the drawing. This pinion is mounted on the shaft 14 so as to rotate therewith and to move longitudinally thereof and thereby engage 70 the flywheel teeth and subsequently rotate the same through its driving connection with 75 such shaft. In the present instance, this pinion is splined onto the shaft 14 by means of the splines 19, and has a longitudinal sleeve or hub 20 which extends toward the gear 17 and which is operatively connected 80 with a shell 21, mounted to slide at its inner end upon the smooth portion of the shaft 14. The sleeve 20 and shell 21 have a telescoping fit and a yielding longitudinal movement, one with respect to the 85 other, by means of the spring 22 and of a pin and slot connection. In the present instance a pin 23 is mounted in the shell 21 and the cooperating slot 24 is formed in the sleeve 20.

The sleeve 12 and the shell 21 are operatively connected so that shifting movements of the sleeve 12 shall be automatically transmitted to the shell. In the present instance the construction and arrangement are 95 such that the shifting of the sleeve 12 longitudinally in one direction causes a shifting of the shell longitudinally in the opposite direction in order that the driving member or pinion 18 may be automatically advanced 100 into mesh with the flywheel and may be automatically withdrawn therefrom when the engine starts on its own power. This operating means which is located between the sleeve and shell and between the two 105 shafts 7 and 14 comprises in the present instance, a rock shaft 25 having its bearings in the side walls of the casing 5 and extend-

ing at right angles to the axes of said shafts 7 and 14. To this rock shaft there are secured on diametrically opposite sides the two yokes 26 and 27, the outer ends of 5 whose arms are adapted to engage respectively the circumferential groove 28 of the sleeve 12 and the circumferential groove 29 of the shell 21. By preference these ends of the arms are provided with rollers 30 and 10 31 which enter said grooves respectively.

Describing a cycle of operation and starting with the normal position of the parts indicated in the drawing, when the electric motor is operated the pinion 10 will be automatically 15 shifted to the left to the dotted line position by reason of the spiral gear teeth on such pinion and on the gear 17, the latter gear rotating in a fixed plane. The result of this shifting of the pinion is 20 to rock the shaft 25 and thereby simultaneously shift the pinion 18 to the right and into mesh with the flywheel, by reason of the operating connection between the yoke 27 and such pinion 18 provided with it by 25 the shell 21 and sleeve 20. A driving connection is now provided from the motor to the flywheel through the shaft 7, sleeve 12, pinion 10, gear 17, shaft 14 and pinion 18.

When the engine has started on its own 30 power and the gear 17 thereupon becomes a driving gear as respects the pinion 10, such latter pinion will automatically shift to the right to its normal position and in such shifting movement it will automatically 35 withdraw the pinion 18 out of mesh with the flywheel by reason of the rock shaft and the yokes which connect the sleeve 12 and the shell 21.

In the event that the teeth of the pinion 40 18 should abut the flywheel teeth end to end jamming is prevented by the yielding connection between the shell 21 and the pinion sleeve or hub 20. When such abutting occurs the pinion 18 will be stopped in its 45 longitudinal movement but the shell 21 will continue to move or slide on the sleeve 20 against the tension of the spring 22. Upon the first rotative movement of the shaft 14 the pinion 18 will be turned so as to bring 50 its teeth into register with the flywheel teeth whereupon such pinion will be projected by the pressure of the spring 22 into full mesh with such flywheel.

I claim:

55 1. An engine starter drive comprising driving and driven shafts, a pinion mounted on the driving shaft for rotary movement therewith and automatic longitudinal movements thereon in both directions, a gear 60 mounted on the driven shaft and meshing with the pinion, a driving member adapted to engage a member of the engine to be started and mounted on the driven shaft for rotary movement therewith and longitudinal 65 movement thereof for engagement with such

engine member and disengagement therefrom, and means for transmitting the longitudinal shifting movements of the pinion to the driving member.

2. An engine starter drive comprising 70 driving and driven shafts, a pinion mounted on the driving shaft for rotary movement therewith and automatic longitudinal movements thereon in both directions, a gear mounted on the driven shaft and meshing 75 with the pinion, a driving member adapted to engage a member of the engine to be started and mounted on the driven shaft for rotary movement therewith and longitudinal movement thereof for engagement with such 80 engine member and disengagement therefrom, and means for transmitting the longitudinal shifting movements of the pinion to the driving member, said means including a rock shaft and connections between it and 85 the pinion and driving member.

3. An engine starter drive comprising driving and driven shafts, a pinion mounted on the driving shaft for rotary movement therewith and automatic longitudinal movements thereon in both directions, a gear mounted on the driven shaft and meshing 90 with the pinion, a driving member adapted to engage a member of the engine to be started and mounted on the driven shaft for 95 rotary movement therewith and longitudinal movement thereof for engagement with such engine member and disengagement therefrom, and means for transmitting the longitudinal shifting movements of the pinion to the driving member, said shafts being 100 arranged parallel to each other, and said means being located between them.

4. An engine starter drive comprising 105 driving and driven shafts, a pinion mounted on the driving shaft for rotary movement therewith and automatic longitudinal movements thereon in both directions, a gear mounted on the driven shaft and meshing with the pinion, a driving member adapted 110 to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said means including a 115 yielding device coöperating with the driving member.

5. An engine starter drive comprising 120 driving and driven shafts, a pinion mounted on the driving shaft for rotary movement therewith and automatic longitudinal movements thereon in both directions, a gear 125 mounted on the driven shaft and meshing with the pinion, a driving member adapted to engage a member of the engine to be started and mounted on the driven shaft for rotary movement with such engine member 130

and disengagement therefrom, a shell mounted axially with respect to the driven shaft and operatively connected with the driving member, and means for transmitting the 5 longitudinal shifting movements of the pinion to the shell.

6. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be 10 started and mounted on the driven shaft for rotary movement with such engine member and disengagement therefrom, a shell mounted axially with respect to the driven shaft and operatively connected with the driving member, and means for transmitting the 15 longitudinal shifting movements of the pinion to the shell, said sleeve being yieldingly connected with the driving member.

7. An engine starter drive comprising driving and driven shafts, a pinion mounted on the driving shaft for rotary movement therewith and automatic longitudinal movements thereon in both directions, a gear mounted on the driven shaft and meshing with the 20 pinion, a driving member adapted to engage a member of the engine to be started and mounted on the driven shaft for rotary movement therewith and longitudinal movement 25 thereof for engagement with such engine member and disengagement therefrom, a shell mounted axially with respect to the driven shaft, and adapted to impart its longitudinal movements to the driving member, a spring between the driving member and shell, and means for transmitting the longitudinal movements of the pinion to the driving 30 member.

8. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement 45 thereof for engagement with such engine member and disengagement therefrom, said driving member being provided with a hub, a shell mounted to slide on such hub and operatively connected therewith, and an operating connection between the pinion and shell.

60 9. An engine starter drive comprising driving and driven shafts, a pinion mounted on the driving shaft for rotary movement therewith and automatic longitudinal movements thereon in both directions, a gear mounted 65 on the driven shaft and meshing with the

pinion, a driving member adapted to engage a member of the engine to be started and mounted on the driven shaft for rotary movement therewith and longitudinal movement thereof for engagement with such engine member and disengagement therefrom, 70 said driving member being provided with a hub, a shell operatively connected therewith, and a spring between the shell and pinion, and an operating connection between 75 the pinion and shell.

10. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary 80 movement therewith and longitudinal movement thereof for engagement with such engine member and disengagement therefrom, said driving member being splined to the driven shaft and being provided with a hub, 85 a shell yieldingly connected with the hub, and an operating connection between the pinion and shell.

11. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement with such engine member and disengagement therefrom, a shell mounted axially with respect to the driven shaft and operatively connected with the driving member, and means for transmitting the longitudinal shifting movements of the pinion to the shell, comprising a rock shaft having 100 connections with the pinion and shell respectively.

12. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement with such engine member and disengagement therefrom, a shell mounted axially with respect to the driven shaft and operatively connected with the driving member, and means for transmitting the longitudinal shifting movements of the pinion to the shell, comprising a rock shaft and yokes connected therewith and operatively engaging the pinion and shell. 125

13. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement with such engine member and disengagement therefrom, a shell mounted axially with respect to the driven shaft and operatively connected with the driving member, and means for transmitting the longitudinal shifting movements of the pinion to the shell, comprising a pair of oscillating connected yokes, said pinion having a hub provided with a circumferential groove engaged by one yoke, and the shell having a circumferential groove engaged by the other yoke. 50
14. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said pinion and gear having spiral gear teeth and the pinion having a wide face so as to be constantly in mesh with the gear. 55
15. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said driving shaft having a smooth portion at one end and splines at the other end, and said pinion having a body adapted to slide on such smooth portion and a hub adapted to engage such splines. 60
16. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said pinion and gear having spiral gear teeth. 65
17. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said pinion and gear having spiral gear teeth, and said driving member being a pinion with spur teeth. 70
18. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said pinion and gear having spiral gear teeth, and said driving member being a pinion with spur teeth. 75
19. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said pinion and gear having spiral gear teeth, and said driving member being a pinion with spur teeth. 80
20. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said pinion and gear having spiral gear teeth, and said driving member being a pinion with spur teeth. 85
21. An engine starter drive comprising driving and driven shafts, a pinion mounted on the driving shaft for rotary movement therewith and automatic longitudinal movements thereon in both directions, a gear mounted on the driven shaft and meshing with the pinion, a driving member adapted to engage a member of the engine to be started and mounted on the driven shaft for rotary movement therewith and longitudinal movement thereof for engagement with such engine member and disengagement therefrom, and means for transmitting the longitudinal shifting movements of the pinion to the driving member, said pinion and gear having spiral gear teeth, and said driving member being a pinion with spur teeth. 90

MAURICE P. WHITNEY.
